UNITED STATES PATENT OFFICE

108,234

DESIGN FOR AN ULLAGE-ROD WIPER

Frank H. Helsley, Los Angeles, Calif.

Application November 12, 1937, Serial No. 72,822

Term of patent 3½ years

To the Commissioner of Patents:

I, Frank H. Helsley, a citizen of the United States, residing at Los Angeles, in the county of Los Angeles and State of California, have invented a new, original, and ornamental Design for Ullage-Rod Wipers, of which the following is a specification, reference being had to the accompanying drawing, forming a part thereof:

Fig. 1 is a perspective view of the wiper, looking downwardly upon the upper surface thereof;

Fig. 2 is a corresponding view, with the wiper inverted by rotation end-for-end;

Fig. 3 is a rearward end elevation of the wiper; and

Fig. 4 is a forward end elevation thereof.

I claim:

The ornamental design for an ullage-rod wiper, as shown.

FRANK H. HELSLEY.
